UNITED STATES PATENT OFFICE

170,128

COMBINATION LAMP AND PLANTER OR SIMILAR ARTICLE

Filmore Charles Levy, Altadena, Calif.

Application September 29, 1952, Serial No. 21,635

Term of patent 14 years

(Cl. D48—20)

To all whom it may concern:

Be it known that I, Filmore Charles Levy, a citizen of the United States, residing in the city of Altadena, county of Los Angeles, State of California, have invented a new, original, and ornamental Design for a Combination Lamp and Planter or Similar Article, of which the following is a specification, reference being had to the accompanying drawing, forming a part thereof.

Fig. 1 is a front elevation view of a combination lamp and planter showing my new design.

Fig. 2 is a top plan view of the same.

Fig. 3 is a sectional view taken along the line 3—3 of Fig. 1.

I claim:

The ornamental design for a combination lamp and planter or similar article, as shown.

FILMORE CHARLES LEVY.
